METHOD AND APPARATUS FOR PRODUCING PILE FABRICS

Walter A. Rice, Amsterdam, N. Y., assignor, by mesne assignments, to Mohasco Industries, Inc., Amsterdam, N. Y., a corporation of New York

Application September 28, 1955, Serial No. 537,215

9 Claims. (Cl. 139—38)

This invention relates to the production of pile fabrics by weaving operations and is concerned more particularly with a novel method, by which pile fabrics having a pile of loops varying in height in accordance with a pattern can be made rapidly and at low cost. The method can be advantageously practiced on a loom forming part of the invention and of the hook type and, if desired, the new loom may be employed in accordance with the method to produce a pile fabric, in which the loops are of uniform height but substantially shorter than those of fabrics made on ordinary hook looms.

Hook looms have been used for many years in the production of pile fabrics and, as usually constructed, such looms have a set of hooks mounted for reciprocation and operated at the proper time in the loom cycle to engage pile warp yarns in the upper line of a shed and draw the yarns out of the shed to form loops. While the loops of pile yarn are so held by the hooks, the weaving proceeds and, when the loops have been bound in place by one or more picks of filling inserted and beaten up, the hooks release the loops and the cycle of operation is repeated. Hook looms are of sturdy reliable construction and can be used to produce fabric at relatively low cost. However, as ordinarily constructed, they cannot produce a fabric having loops of different height and also the loops of a hook loom fabric are much longer than is desirable for some purposes.

The present invention is, accordingly, directed to the provision of a method of weaving, which can be utilized in the production of fabrics having pile loops varying in height as determined by a pattern and the invention further includes a new form of hook loom for practicing the invention.

For a better understanding of the invention, reference may be made to the accompanying drawings, in which

Fig. 1 is a diagrammatic side elevational view with parts broken away of a hook loom modified for the practice of the method of the invention;

Fig. 1A is a detailed view showing the manner of inserting the filling yarns into the shed;

Fig. 2 is a sectional view on the line 2—2 of Fig. 3;

Fig. 3 is a fragmentary front elevational view of the loom;

Fig. 4 is a view in elevation of a pattern member employed in the loom;

Figs. 5—8, incl., are diagrammatic views illustrating the operation of the loom; and

Fig. 9 is a detailed view showing the manner of applying a stepwise movement to the pattern drum.

The loom shown has sides 10 and is equipped with the usual harness motion 11 including the heddle frames 12,

2

13, and 14 controlling the pile warp yarns 15, the stuffer warp yarns 16, and the binder warp yarns 17, respectively. As is customary, the pile warp yarns are drawn from spools in a frame or creel, while the stuffer and binder warp yarns are supplied from respective beams. The 5 loom has a shuttle motion or a needle motion for inserting filling yarns in the warp sheds and the inserted yarns are beaten up by the usual lay including a reed 18 mounted on swords 19 fast on a rocker shaft (not shown). In Fig. 10 1A the needle N for inserting the filling yarn into the sheds is illustrated in section and the two parts of the loop of filling yarn lying in the eye of the needle and carried across the shed are designated at 38.

At the front of the loom, a breast beam 20 is mounted 15 between upward extensions 10a of the sides and the extensions are provided at their tops with grooves serving as guideways, in which a bar 21 extending across the loom a short distance above the breast beam is mounted for reciprocation lengthwise of the yarns. The bar is provided with a plurality of hook members 22 in the form of thin flat wires and the members extend through the dents in the reed 18 to terminate in heads 23 lying vertically between the yarns at the side of the reed adjacent the harness motion. Each wire has a hook 22a formed on 20 its lower edge and bent out of the plane of the wire, the hook pointing toward the breast beam. The bar 21 is reciprocated in the guideways by rocker arms 24 pivoted on the frame extensions 10a and actuated by links 25 connected to arms 26 on a rocker shaft 27. The links 25 are 25 provided with an adjustment device 28, such as a turn buckle, for varying the length of the links and thus varying the length of the path of travel of bar 21.

The pile warp yarns on their way from the spools to the harness 12 pass over a fixed gripping member 29, 30 which is mounted between upward extensions 10b of the loom sides and has its top faced with a layer of yielding material, such as leather. A drum 30 carrying a plurality of radial pattern members 31 is mounted above the fixed gripping member 29 with its shaft 32 supported in bearings in arms 33, 34. The arms are provided with screws 35 threaded through the arms and into the tops of the extensions 10b, so that the arms can be raised and lowered by the screws to vary the position of the drum relative to the fixed gripping member 29. 35 The screws are provided with lock nuts 36. The drum is driven from one of the shafts of the loom through a ratchet and pawl device and chain 37 and is advanced stepwise to bring the pattern members 31 successively into effective position in relation to the fixed gripping member 29. After a member 31 is in effective position, the drum remains at rest during the insertion and beat-up of at least one filling yarn. The ratchet and pawl device for driving the drum is illustrated in Fig. 9. In this figure a ratchet wheel 39 is mounted on a shaft carrying a sprocket wheel (not shown), about which chain 37 is trained. An arm 40, loose on the shaft, carries a spring-actuated pawl 41 engaging the ratchet wheel. The ratchet wheel is held against return movement by a stop pawl 42. The arm 40 is connected by a link 43 to an arm 44 fast on the rocker shaft 27 so that as the bar 21 carrying the hooks is moved by the rocker shaft, the ratchet wheel is advanced to advance the pattern drum stepwise in timed relation to the operation of the hooks. 40 45 50 55 60 65 The pattern member 31 in effective position engages

the facing 29a on the fixed gripping member 29, and the members 31 are so formed that they can clamp pile yarns determined by the pattern against the member 29, while other pile yarns may pass between members 29 and 31 without being clamped. To achieve this result, the outer edge of each pattern member 31 is divided into sections adapted to act on individual yarns and, at those sections, such as section 31a, which are to grip the yarns, the member 31 is of full width, while, at other sections, such as section 31b, the member is cut away, so that the yarn opposite those sections pass freely between members 29 and 31. The arrangement of the cut-outs in the edges of the members 31 varies in accordance with the pattern and the members mounted on the drum form a set employed in producing a repeat of the pattern.

The cycle of operation of a form of the new loom equipped with a needle motion is illustrated diagrammatically in Figs. 5-8, incl., in which the action of hook member 22 is that of all the hook members. In Fig. 5, the hook member is shown in the release position after having released a pile yarn loop 15a, and the hook member remains in that position, until after the beat-up of the filling shot 38a. As soon as the beat-up of shot 38a has been completed, the second shed of the cycle is formed with the pile yarns in the upper line, as shown in Fig. 6. The hook member then moves to the rear, until its hook 22a has passed between the pile yarns, and at once reverses direction and moves forward from its position shown in Fig. 6 to its position shown in Fig. 7. In its forward movement, the hook 22a of the member engages the pile yarn 15 and draws it out of the top line of the shed to form the loop 15b. During the movement of the hook member to the rear and then forward, the second filling shot 38b of the cycle is inserted and beaten up and, while the hook member continues to hold the loop 15b of pile yarn, the third shed of the cycle, shown in Fig. 7, is formed and the third filling shot 38c is inserted in the shed and beaten up to bind the loop in place.

The pile yarn 15, shown in Figs. 5-8, incl., is one, which has been gripped between a pattern member 31 and the fixed gripping member prior to the forward movement of the hook member 22 with its hook 22a drawing the yarn out of the shed to form loop 15b. Accordingly, the drawing out of the yarn to form the loop has stretched the yarn, as indicated by the arrows in Fig. 7, and has placed it under substantial tension.

As soon as the filling shot 38c binding the loop has been beaten up, the hook member moves back a short distance to its release position, where it is shown in Figs. 5 and 8. In this movement, the hook 22a on the member is disengaged from the loop and, as soon as this occurs, the tension on the yarn causes it to contract. As a result, part of the yarn in the loop is drawn out, as indicated by the arrows in Figs. 5 and 8, and the loop is reduced in height. The fourth shed of the cycle is formed, as the hook member moves to the release position, and the fourth filling shot 38d is inserted in the shed and beaten up. The cycle is now completed and is repeated indefinitely.

During each cycle of the weaving operation, the pile yarns 15, which are not gripped between the gripping member 29 and a pattern member 31, are drawn out by their hook members to form loops, as shown in Fig. 7, but, since the yarns are not restrained by members 29 and 31, they are not put under tension, as they are drawn out. Accordingly, when the hook members move to the release position to free the loops of such yarns, the loops remain at their full height and, by proper formation of the pattern members, the pile of the fabric may be formed of high and low loops in any desired arrangement.

In the operation of the loom, the rotation of the pattern drum is timed in relation to the action of the hook members, so that a pattern member 31 is in effective position clamping selected yarns against the fixed grip-

ping member 29 before the hook members have completed their drawing out of the yarns to form the pile loops. If the maximum difference in height between the high loops and the low loops is desired, the pattern members are brought to effective position before the hook members begin to draw out the pile yarns, but the clamping action may start somewhat later, in which event less tension is imposed on the gripped yarns and their loops are reduced in height to a less extent. In all cases, the pattern members remain in effective relation to the gripping member, until after the hooks have released their loops, so that the tension on the yarns may have full effect in reducing the height of the loops.

When it is desired to produce a plain fabric having loops of a uniform height but of less height than those of fabrics produced on an ordinary hook loom, the pattern members employed are of uniform width from end to end, so that each member will grip all the pile warp yarns, when it is in effective position. Accordingly, all the yarns are placed under tension, as they are drawn out to form pile loops, and all the loops are reduced in height to the same extent by the tension, when they are released by the hooks. Since all the pattern members used in producing a fabric with loops of uniform height are alike, the set of pattern members may be replaced by a single member reciprocated toward and away from the fixed member 29.

In the production of fabrics with loops of uniform height, the height may be varied by varying the tension on the yarns and this can be accomplished by altering the timing of the gripping action in relation to the drawing out of the pile yarns by the hooks. The maximum tension is imposed on the yarns and the greatest reduction in the height of the loops occurs, when the yarns are gripped before the drawing out of the yarns starts. To obtain longer loops, the gripping action is delayed until after the drawing out of the yarns begins and the longer the delay in the gripping, the longer will be the loops.

I claim:

1. A method of weaving a pile fabric, which comprises forming sheds of pile and binder warp yarns, inserting a filling yarn into each shed and beating up the inserted yarn, periodically drawing the pile warp yarns out of the top line of sheds to form pile loops, retaining the yarns drawn out in loop form until after the insertion and beat-up of a filling yarn binding the loops, clamping selected pile warp yarns to be drawn out of a shed to form loops by gripping the yarns at the side of the shed remote from the fell of the fabric, and releasing the pile yarn loops and the clamped yarns in that order.

2. The method of claim 1, in which the clamping of the pile warp yarns is effected after the drawing out of the yarns to form loops is started.

3. The method of claim 1, in which the release of the loops occurs a sufficient length of time before the release of the clamped yarns to enable the tension in the clamped yarns to reduce the size of the loops.

4. A loom for weaving a pile fabric containing interwoven pile and binder warp yarns and filling yarns with the pile warp yarns having loops projecting out of the body of the fabric to form the pile, the loom having a harness motion for forming sheds of the warp yarns, means for inserting filling yarns into the sheds, and lay means for beating up the inserted filling yarns, characterized in the provision of hooks for drawing pile warp yarns out of the top line of sheds to form pile loops, clamping means for gripping selected pile warp yarns at the side of the harness motion remote from the lay means, and means for operating the hook means and the clamping means in timed relation to cause the clamping means to grip the pile warp yarns before the hook means completes the loops and the hook means to release the loops before the clamping means releases the gripped yarns.

5. The loom of claim 4, in which the clamping means includes a fixed member, an endless series of movable members, the fixed and movable members lying on oppo-

site sides of the pile warp yarns on their way to the harness motion, and means for advancing the series of movable members to cause the members thereof to clamp selected yarns against the fixed member.

6. The loom of claim 5, in which the movable members are flat wires and the fixed member has a yielding surface, against which the movable members clamp the selected pile warp yarns.

7. The loom of claim 5, in which the movable members are advanced intermittently and clamp the yarns 10 during periods of rest of the members.

8. The loom of claim 5, in which the movable members are mounted upon an endless carrier.

9. The loom of claim 8, in which the carrier is a drum carrying the wires on its surface.
